UNITED STATES PATENT OFFICE.

PAUL FRIEDEL, OF BOHLEN, GERMANY.

DEVICE FOR STOPPING RAILROAD VEHICLES INDEPENDENTLY OF THE DRIVER.

Application filed July 15, 1926, Serial No. 122,650, and in Germany June 14, 1926.

This invention relates to a device for stopping railroad vehicles independently of the driver in case the stop signal should remain unnoticed, and the invention consists in the provision of a track apparatus in the form of a resiliently supported platform arranged so as to be depressed by the vehicle wheels, a pivoted arm which is controlled by the platform, being arranged so as to turn, under the movement of the same, into position for engagement with a brake and signalling lever on the vehicle. Means are provided whereby the platform and its arm are moved horizontally into and out of operative position together with the operation of the semaphore.

Fig. 1 of the accompanying drawings represents a side view of the device on the point of being operated,

Fig. 2, a view of the vehicle portion of the apparatus in operated position,

Fig. 3, a view of the device at right angles to Fig. 1,

Fig. 4, a plan of the same,

Fig. 5, a section of the track apparatus on the line V—V of Fig. 4 and on an enlarged scale,

Fig. 6, a section at right angles to Fig. 5, and

Fig. 7, a plan of the track apparatus on a still larger scale.

Arranged on the railroad track near one of the rails 1, is a casing 7 in which a platform 3 is resiliently supported on a level with the rail head. The platform is guided by vertical bolts 4 in a supporting plate 5 and bears against the latter by means of springs 6 arranged on the bolts. The supporting plate 5 is held in guideways in the casing walls 8 so that it can be operated for shifting the platform 3 towards and away from the railhead. Springs 15 connected to the casing wall 14 and to the platform 3 tend to hold the latter against the rail head so that it will be engaged and depressed by the rim 34 of the wheel 35 of a passing vehicle, as shown in Fig. 3. The shifting of the platform 3 away from the rail into its inoperative position is effected automatically when the semaphore signal is set on "clear". For this purpose the plate 5 is connected at 16 to a rope 17 which is guided over a sheave 18 in the casing 7 and which is attached through the medium of a spring 33 to a rope 20. The latter passes over a deflecting pulley 19 and is connected to the rope 21

which rotates the wheel 22 whereby the control rod 23 of the arm of the semaphore 2 is operated. The spring 33 allows the rope 20 to move independently of the plate 5 whose movement is limited by the casing wall 32.

The depression of the platform 3 by the wheel rim 34 is utilized for applying the brake of the vehicle. For this purpose the vehicle frame 24 is fitted with a double-armed lever which rocks about a pivot 27. The lower, bent arm 25 of this lever is arranged so as to pass across the platform 3 if the latter is in operative position. The upper arm 26 of the lever is connected by ropes 30 and 31 with the audible signalling device and the air-brake of the vehicle so that they will be operated if the lever is turned into the position shown in Fig. 2. This turning of the lever is effected by means of an arm 11 which is guided in a split 12 in the platform 3 and brought up through said split when the platform is depressed, so as to enter the path of the lever arm 25. The arm 11 is mounted loosely on a shaft 9 which is held in brackets on the casing wall 8. Another arm 10 which controls the arm 11 is connected by a link 13 to the platform 3 so that when the latter is lowered, the arm 11 is turned up through the slit 12. The arm 11 projects through an elongated aperture in the casing wall 8 and follows, together with the arm 10 and the link 13, the horizontal adjustment of the platform 3 by sliding on the shaft 9.

The springs 15 maintain the device in operative position so long as the semaphore arm is raised. If a vehicle should pass the signal, the lever 25, 26 will be operated by the arm 11, the audible signal of the vehicle will be sounded as a warning to the driver and the brake will be automatically applied. If the road should be clear, and the semaphore arm is lowered accordingly, the platform 3 will be pulled away from the rail 1 by the ropes 20 and 17, and as it is now out of reach of the wheel rim 34, the vehicle can pass the signal without being affected by the device.

The lever arm 25 is preferably fitted with a spring-pressed notch 28 which co-operates with a toothed rack 21 for retaining the lever in operated position.

If the signal and brake are operated electrically, the ropes 30 and 31 are substituted by suitable switch elements.

The springs 15 may be replaced by

weighted levers such as are usually employed in the operation of railroad points.

I claim:

1. In a device for stopping railroad vehicles independently of the driver, the combination with a signal and brake operating lever on the vehicle and an actuating arm mounted on the track, of a resiliently supported platform adapted to be depressed by engagement with the wheels of the vehicle and to prepare said arm for engagement with the operating lever when thus depressed, a horizontally adjustable supporting plate for said platform, bolts

connected to the platform and guided in said plate, supporting springs arranged on the bolts so as to bear against the plate and support the platform, springs tending to hold the platform against the track rail in operative position, and a rope acting on the supporting plate for shifting the latter and the platform out of operative position.

2. The structure claimed in claim 1 in combination with a spring incorporated with said rope, and connection between the rope and the semaphore signal for simultaneous operation.

PAUL FRIEDEL
